Thos W. R. McCabe
John Aldersheim

ATTORNEY.

UNITED STATES PATENT OFFICE.

THOMAS W. R. McCABE, OF PHILADELPHIA, PENNSYLVANIA.

APPARATUS FOR GRINDING LATHE-CENTERS.

SPECIFICATION forming part of Letters Patent No. 394,786, dated December 18, 1888.

Application filed May 14, 1887. Serial No. 238,178. (No model.)

To all whom it may concern:

Be it known that I, THOMAS W. R. McCABE, a citizen of the United States, residing in the city and county of Philadelphia, State of Pennsylvania, have invented a new and useful Improvement in Apparatus for Grinding Centers of Lathes, which improvement is fully set forth in the following specification and accompanying drawings.

10 My invention relates to improvements in apparatus for grinding centers of lathes; and it consists in the construction and combination of parts as herein set forth.

Figure 1 represents a partial plan view and 15 partial horizontal section of an apparatus for grinding lathe-centers embodying my invention. Fig. 2 represents a view of the facing-piece thereof. Fig. 3 represents a section in line $x\ x$, Fig. 2. Fig. 4 represents a section 20 in line $y\ y$, Fig. 6. Fig. 5 represents a section in line $z\ z$, Fig. 4. Fig. 6 represents a top view of the bearing portion of the grinding-wheel.

Similar letters of reference indicate corresponding parts in the several figures.

Referring to the drawings, A represents the "center" of a lathe, the same being connected with the rotatable head or disk B, and C represents the tool-post, which features are 30 of well-known construction.

D represents a frame, which has an arm, E, for securing the same to the tool-post, said frame being adapted for supporting the parts of the apparatus embodying my invention.

35 Within the boss A', at one end of the frame, is a rotatable sleeve, F, within which is a shaft, F', connected with said sleeve by a feather, so as to rotate therewith. To the outer end of the shaft F' is secured a pulley, G, which has a beveled face, a, and is adapted to be placed in frictional contact with the head B, it being noticed that the shaft F' is set obliquely to the axis of said head. To the end of the boss A' is fitted a set-screw, H, 45 which bears against a spring, H', at the end of the shaft F' opposite to the pulley G for holding the latter in operative position against the head B.

In order to prevent motion of the screw H 50 after adjustment, I employ a jam-nut, J, which

is fitted on said screw and tightens against a collar, J², which is secured to the sleeve F by a screw, J³.

At the end of the frame A opposite to the boss A' is a boss, A², which is parallel with 55 said boss A' and likewise oblique to the axis of the head B. Within the boss A² is a rotatable sleeve, K, to the exterior of which is secured a pulley, N, which enters a recess, b, in the boss A². Through the sleeve K is 60 passed a shaft, P, which is connected with said sleeve by a feather, whereby the shaft may be moved in opposite directions or in and out while receiving rotation from the pulley N. The end of the shaft toward the head B 65 carries an emery or other grinding wheel Q, which, as will be seen, has its periphery contiguous to the lathe-center A and parallel with the side thereof. The opposite end of the shaft carries a knob, R, for convenience 70 of working the shaft P in and out of the sleeve K as its bearings.

Secured to the sleeve F is a pulley, F², around which passes an endless belt or band, S, which also passes around the pulley N, so as to operate the latter.

It will be seen that when the apparatus is located in position and secured to the tool-post the pulley G is advanced against the head B and held thereat by the spring H. 80 The pulley receives motion from the head B, which, as well known, constitutes part of the lathe and is now running, and causes the rotation of the sleeve F, and consequently of the pulley F². Owing to the belt S, power is 85 communicated to the pulley N, and consequently to the shaft P, whereby the grinding-wheel Q is rotated. The wheel Q, as running, is now moved along the side of the center by drawing the shaft P in and out of the sleeve 90 K, said sleeve and shaft, however, continuing its rotation. In this manner the center may be quickly and uniformly ground, and when the work is accomplished the apparatus may be readily disconnected from the tool-post and 95 removed.

Owing to slots existing in the head B, it is desirable to cover the same in order to prevent irregular motion of the pulley G. For this purpose I employ a facing-plate, T, which 100

is temporarily secured to the head B and has a central opening, c, through which the center A projects.

In lieu of the belt S, the pulleys F² N may 5 be of the form of pinions or spur-wheels which mesh with each other, and thus cause the rotation of the grinding-wheel.

As the shaft F' is connected with the sleeve F by a feather, said shaft may slide in and 10 out of said sleeve, whereby the friction-disk may be set or adjusted relatively to the distance of the head B from the frame D.

The pressure of the spring H' against the 15 shaft, and consequently against the friction-pulley G, is adjusted by the screw H.

Having thus described my invention, what I claim as new, and desire to secure by Letters Patent, is—

1. In an apparatus of the character named, 20 the frame D, having a boss, A', in combination with the sleeve F, carrying fixed pulley F², the shaft F', rotatably secured to said sleeve and carrying the bevel-faced pulley G, the collar J², secured to sleeve F by screw J³, the 25 screw H in end of collar J², and the spring H' between shaft F' and screw H, substantially as and for the purpose set forth.

2. In an apparatus of the character named,

a boss with sleeve having a bearing in said boss, a shaft longitudinally movable in said 30 sleeve and having a bevel-pulley thereon, a spring bearing against the end of said shaft, the collar J², secured by screw J³ to said sleeve, and a screw, H, bearing against said spring, said parts being combined substantially as 35 and for the purpose set forth.

3. An apparatus of the character named, consisting of the frame D with the bosses A' A², the sleeve F, journaled in the boss A' and carrying the pulley F², the shaft F', rotatably 40 secured to the sleeve F by a feather-connection and carrying the bevel-faced pulley G, a spring and screw adjusting mechanism secured to said sleeve F for said shaft F', the sleeve K, journaled in the boss A², the shaft 45 P, having feather-connection with said sleeve K and carrying the emery-wheel Q, a pulley connected to said sleeve K, and the band S, connecting the pulley F and the pulley on sleeve K, said parts being combined substantially as described.

T. W. R. McCABE.
